ATTACHMENT MEANS FOR CONTROL APPARATUS ON
ENGINES

This application is a continuation of my prior application Ser. No. 721,854 filed Apr. 16, 1968 and now abandoned.

This invention relates to means for attaching fuel control apparatus to internal combustion engines and has particular, though not exclusive, utility in relation to fuel control apparatus for use on aircraft engines.

The object of the invention is to provide attachment means of the kind referred to in a convenient form.

In accordance with the present invention attachment means for a fuel control apparatus comprises formations on a body of the control apparatus engageable with complementary formations on a part on or securable to the associated engine, such formations enabling simultaneous mechanical, fuel passage and/or other connections to be affected as the body and said part are fastened together.

The invention will now be described by way of example with reference to the accompanying drawings in which:

FIG. 1 illustrates diagrammatically one form of apparatus incorporating this invention.

FIG. 2 is a side elevation view of apparatus having the invention, and

FIGS. 3 and 4 are end elevation and side views respectively of a part on the apparatus of FIG. 2.

The examples illustrated in FIGS. 1 and 2 are intended for use on an internal combustion engine for a light aircraft, the engine being indicated at 10.

The engine 10 has attached to it a fuel control apparatus which, in this example, includes an engine driven pump, and means for metering the quantity of fuel delivered to the engine, this apparatus being mounted in a single body 11.

In order to effect attachment between the body 11 and the engine 10 there is, in the FIG. 1 example, a part 12 which is itself secured to the engine 10, and to which the body 11 is secured in any convenient detachable manner.

The part 12 has a plurality of external connections which include fuel pipe connections at 13 and 14, air pipes at 15 and 16, and a mechanical connection at 17 to an operator's throttle control. The throttle itself, however, is disposed in the body 11, and is indicated generally at 18.

The part 12 also has a connection with the engine 10, whereby the pump in the body 11 can be driven (this is not illustrated) and if desired, other connections can be made to the part 12, such as electrical connections.

Between the body 11 and the part 12 are various forms of connectors which establish communication between the pipes, mechanical connections and passages or apparatus in the body 11. The throttle 18 is connected with its external connection 17 on the part 12 through a splined spindle 19, which projects from the part 12, to engage in a complementarily splined portion of the throttle 18. Preferably, the splined shaft 19 is only capable of engaging with the throttle 18 in one angular position. Other forms of connection between the throttle and the external connection 17 can be substituted if required.

There is a slave shaft 20 which is splined at both ends, which is engageable with the pump in the body 11. This slave shaft

20 is connected, within the part 12, to an engine driven member (not shown). It is, however, to be understood that other forms of detachable driving connection can be provided between the engine and the pump in the body 11 through the part 12.

In the example shown in FIG. 1, there is a sealing plate 21 between the part 12 and the body 11, and through this extends a sealed sleeve 22 which is carried by the part 12 and is engageable in a bore in the body 11 to provide a substantially fluid, tight joint. There is also a face seal 23 which may be used in combination with the sealing plate 21, or alternatively the latter may be omitted and the face seal may be carried either in the part 12 or in the body 11 to engage the opposing surface when the body 11 is secured to the part 12.

15 Other alternative sealing and connecting arrangements can be incorporated, but in all cases connection between all of them can be achieved simultaneously as the body 11 is moved toward the part 12 to affect securement thereto.

In the alternative arrangement, shown in FIG. 2, the part 12 is formed integrally with an appropriate casting of the engine itself, all the external connections are made to the engine in a manner not shown.

FIGS. 3 and 4 show a part 24 which is connected to the body 11 by means of a central screw engaging in a hole 25. This part 24 is of disc like form and has bonded to one face a sealing plate 26. The part 24 has a hole 27 for reception of a driving shaft (not shown) from the engine 10 and a further set of holes 28, which are fuel supply passages. There are, as in the FIG. 1 constructions, complementary formations on the apparatus 11 and the engine 10 respectively.

30 It will be seen that this arrangement enables rapid maintenance and/or testing of the fuel control apparatus of the body 11 to be accomplished without disturbance of any of the external connections, which are required to the apparatus.

I claim:

1. In an internal combustion engine having a fuel control unit and attachment means between the fuel control unit and the engine, said attachment means including a part secured to the engine and securable to the fuel control unit, said part having a plurality of internal passages for fuel and air, said internal passages terminating at one end in external exposed connections for fuel and air lines and terminating at their opposite end at apertures in a plane surface forming a mounting face for a complementary shaped face on the fuel control unit, said

40 fuel control unit having corresponding passages terminating in apertures in the mounting face in registry with those in said part, said part having at least one external mechanical linkage engaged with mechanical connecting means in said part which is engageable with a mechanical device in the fuel control

45 unit, means for removably securing the fuel control unit to said part whereby said passages and mechanical device become simultaneously operably connected to afford connection between the fuel and air lines and the mechanical linkage respectively, and a single separate sealing means disposed

50 between the mounting faces to prevent leakage between passages.
